Frank E. Liverance, Jr.
Attorney.

UNITED STATES PATENT OFFICE.

HENRY F. FRALICK, OF GRAND RAPIDS, MICHIGAN.

HORSESHOE.

Application filed September 15, 1924. Serial No. 737,637.

To all whom it may concern:

Be it known that I, HENRY F. FRALICK, a citizen of the United States of America, residing at Grand Rapids, in the county of Kent and State of Michigan, have invented certain new and useful Improvements in a Horseshoe; and I do hereby declare the following to be a full, clear, and exact description of the invention, such as will enable others skilled in the art to which it appertains to make and use the same.

This invention relates to a novel construction of horseshoe, one in which one part of a two-part horseshoe is nailed to a hoof and a second part is placed under and detachably connected to the first part. On said second part, the usual calks for engaging the road are formed which, when the same become worn, this part of the shoe may be readily removed and the calks repaired or sharpened or a new part may be substituted in place of the old one removed. My invention consists in a novel form of construction for making a secure connection of the parts of the horseshoe so that the same cannot loosen under the service to which the shoe is subjected. There is also provision made for cushioning the shock to which the hoof is subjected when the shoe strikes the road in service and, furthermore, the calks are located in such manner that the collection of snow in winter time therein is practically obviated and side slip on roads overcome. Various other novel features of the construction together with the advantages coming therefrom will appear as understanding of the invention is had from the following description taken in connection with the accompanying drawing, in which,

Fig. 1 is a perspective view of the under detachable part of the horseshoe showing the calks thereon.

Fig. 2 is a perspective view of the other part of the shoe or that part which is securely attached to the hoof.

Fig. 3 is a longitudinal vertical section through the assembled shoe, and

Fig. 4 is a fragmentary plan of the front end portion of the under detachable part of the shoe.

Like reference characters refer to like parts in the different figures of the drawing.

The part 1 of the horseshoe, shown in Fig. 2, is of the usual form having two arms 2 extending from the opposite sides of the middle portion of said part of the shoe

through which openings are made for the passage of horseshoe nails in attaching this part of the shoe to the hoof. At the middle portion of said part 1 a boss 3 of circular form is integrally cast projecting downwardly for a short distance and having an opening 4 made therethrough which is interiorly threaded. At the ends of the arms 2 and on the under side flat relatively shallow projections or off-set portions 2^a are formed through each of which an opening 5 also interiorly threaded is made, as shown in Fig. 2.

The other part of the shoe includes a middle portion 6 at one end thereof through which an opening 7 is made large enough that the boss 3 may pass freely through it. A relatively wide calk 8 is located at right angles at the outer edge of the portion 6 and near the opening 7 this calk is provided with an integrally cast lug 9 for a purpose which will hereafter appear. Two diverging arms 10, curved substantially as the arms 2, extend from the middle portion 6 and at the ends and at the outer sides of said arms triangular shaped calks 11 are formed as shown in Fig. 1, it being noted that these calks extend diagonally with respect to each other and at an angle to the longitudinal center line of the shoe. As shown the calks are all sharpened but it is evident that they may be of any desired form, the particular design of the same not being an absolutely essential feature of the invention.

In the arms 10 near the outer ends thereof diagonal slots 12 are cut so positioned that when the said under part of the shoe is placed against the part first described, with the boss 3 passing through the opening 7, the slots may be made to come into conjunction with the threaded openings 5 in the arms 2 of the first described part of the shoe. The part 1 of the shoe is nailed to the hoof and the under part secured to the part 1 by placing it against said part 1 with the boss 3 passing through the opening 7. A screw 13 having a head 14 is screwed into the threaded opening 4 until the head comes into engagement with the shoulder 9 formed on the calk 8. This occurs when the screw 13 has been given a few turns or enough to properly start the same. After this the under part of the shoe is turned about the axis of the screw 13 and after head 14 is seated against the lug 9, the

screw turns with the under part of the shoe until it is fully driven home with the head 14 brought snugly against the under side of the part 6 of the shoe around the opening 7. In practice on the upper side of the central portion 6 of the under part of the shoe two lugs or offset projections 6^a are integrally formed with a recess between them in which a leather washer 15 may be located, the same surrounding the boss 3 when the parts of the shoe are put together. The front end of the upper portion of the shoe is brought snugly against this washer and into close proximity if not directly in contact with the upper sides of the off-set portions 6^a. These lugs 6^a together with the projections 2^a on the part 1 of the shoe provide space so that the under part of the shoe may be turned freely without coming in contact with the heads of the horseshoe nails, which have been used to secure the part 1 to the hoof. The under part of the shoe is turned until the slots 12 come into alignment with the opening 5 and screws having heads 14^a are passed through the slots into said opening thereby binding the arms 10 to and against the arms 2, this completing the connection between the two parts of the shoe.

30 The construction of horseshoe described is very practical and has proved very satisfactory in use. The parts thereof are made of malleable iron, preferably. The locating of the head 14 of screw 13 against the lug 9 insures against outward movement of the screw and that the parts of the shoe will not come apart under the heavy service to which it is subjected. When the calks become worn the under part of the shoe is readily removed by first removing the screws 14^a and then turning the under part of the shoe so as to unscrew the part 13. The calks may then be sharpened and the lower part replaced or, if it is too much worn, a new part may be substituted. The slots 12 permit a certain latitude or range in reshaping the parts for fitting the shoe to be shod.

50 As before stated, the offset portions or lugs 2^a, in conjunction with the parts 6^a, allow the under part of the shoe to swing freely over the nail heads. The leather washer 15 softens and cushions the shock while the boss 3, in conjunction with the screw or stud 13 therethrough, centers the parts so that practically all strains are taken by said stud. In addition an important feature of the invention is the location of the calks 11 at the outer edges of the arms 10 diagonally positioned so that snow, which normally might be picked up and held between the calks 11, is permitted to freely slide out between them. The diagonal position of the calks also in conjunction with the triangular shape of the calks is of value in

insuring against side slip, as is evident. These various features combine to make the structure one of merit as has been proved in practice. The invention is defined in the appended claims and is to be considered as 70 comprehensive of all forms of structure coming within their scope.

I claim:

1. In a horseshoe, a part shaped to fit a hoof and be permanently attached thereto 75 and formed between its ends with a downwardly projecting boss interiorly bored and threaded, a second part adapted to lie against the first part having a portion at one end with an opening therethrough for 80 the passage of said boss and formed with a downwardly projecting calk having a shoulder adjacent said opening on the inner side of the calk, said second part of the shoe having outwardly diverging arms extending from said end portion which terminate in downwardly turned calks, each of the said arms near its end having a slot therein and the first mentioned part having two interiorly threaded openings over which the said 90 slots are adapted to come, and set-screws passing through the slots into said openings and into the boss, the head of the screw passing into the boss bearing against the shoulder on the first mentioned calk to hold 95 the screw against loosening, substantially as described.

2. In a two-part horseshoe, a part substantially U-shaped to fit a hoof and adapted to be permanently attached thereto, said part being formed with a downwardly projecting boss having an interiorly threaded opening therethrough at a point between its ends, a second part located under the first part having diverging arms located substantially under the first part and formed at its upper side with upwardly projecting lugs with a recess between them, a washer located in said recess, said second part having an opening around which the washer is placed and through which the boss on the first part passes, a screw threaded stud passing through said opening into the boss, means for connecting the arms of the said second part to said first part, said second part of the horseshoe being formed with downwardly extending calks located one at the free end of each arm and one at the middle portion of said second part of the horseshoe in front of said stud, substantially as and for the purpose described.

3. In a two-part horseshoe, a part substantially U-shaped to fit a hoof and adapted to be permanently attached thereto, said part at its ends being formed with downwardly extending offset portions on its under side, and substantially at its middle being formed with a downwardly extending boss having a screw-threaded opening therethrough, a second part to the horse-

shoe located under the first part having a middle portion and two diverging arms each of said arms at its free end and at the outer side thereof being formed with a 5 downwardly extending triangular shaped calk, said calks being located diagonally with respect to each other and to the central longitudinal axis of the said second part of the horseshoe, and at its middle portion 10 being formed with a downwardly extending calk, said second part at its middle portion and at its upper side being formed with spaced apart upwardly extending projections with a recess between them and with an opening through which the said boss may 15 pass, a washer located in the recess, a screw threaded stud passing through said opening into the boss and screws passing through the ends of the arms into threaded openings in the ends of said first part. 20

In testimony whereof I affix my signature.

HENRY F. FRALICK.
